GEORGE V. METZEL, OF BALTIMORE, MARYLAND.

Letters Patent No. 88,975, dated April 13, 1869.

STENCIL IMPRESS.

The Schedule referred to in these Letters Patent and making part of the same.

To all whom it may concern:

Be it known that I, GEORGE V. METZEL, of the city of Baltimore, in the State of Maryland, have invented a new and useful article of manufacture, which I denominate a Stencil Impress; and I do hereby declare the following to be a full and correct description of the same, reference being had to the accompanying drawing, which is a perspective view of the article in the act of passing over a stencil-plate.

The invention consists in the substitution for the brush hitherto used in making stencil impressions of a roller, covered with plush, velvet, carpeting, or other similar materials, said roller being impregnated with the coloring-matter, and then passed over the stencil-plate.

So far as I have been able to ascertain, stencilling is invariably performed with a brush, which is applied by hand to the letters on the stencil-plate in succession, it being a matter of some skill, and more time to produce a good impression, uniform in appearance and color.

By the use of my rollers, impressions are made with great rapidity and uniformity, and with much less labor to the operator.

In making my rollers, I select the material for the covering with reference to the character of the work to be done. For fine plates, with small letters, velvet is preferred. Plush is excellent for coarser work, while for very large plates, carpeting, with a heavy pile, is found to answer admirably.

To use the impress roller, dip it in the coloring-matter, and roll it on a flat surface, to equalize the distribution of color. It is then ready to be applied to the stencil-plate, and produce the required impression.

A considerable number of impressions can usually be made without renewing the application of the coloring-matter to the roller.

What I claim, as a new article of manufacture, is—
A stencil impress, consisting of a roller, covered with plush, velvet, carpeting, or other similar material, constructed in the manner described and shown, and applied to the purpose specified.

The above specification of my said invention signed and witnessed at Washington, this 3d day of March, A. D. 1869.
